UNITED STATES PATENT OFFICE.

HARRY F. GEIST, OF RACINE, WISCONSIN, ASSIGNOR TO WEBSTER ELECTRIC COMPANY,
OF RACINE, WISCONSIN, A CORPORATION OF WEST VIRGINIA.

IGNITION MECHANISM FOR INTERNAL-COMBUSTION ENGINES.

1,231,149.

Specification of Letters Patent. Patented June 26, 1917.

Application filed September 20, 1915. Serial No. 51,631.

To all whom it may concern:

Be it known that I, HARRY F. GEIST, a citizen of the United States, residing at Racine, in the county of Racine and State 5 of Wisconsin, have invented a certain new and useful Improvement in Ignition Mechanism for Internal-Combustion Engines, of which the following is a full, clear, concise, and exact description, reference being had to 10 the accompanying drawings, forming a part of this specification.

My invention relates to ignition mechanism for internal combustion engines, and particularly to that type of ignition mechanism 15 which comprises a magneto arranged to be driven by an associated engine, the magneto being so related to make and break contact mechanism located within the combustion chamber of the engine as to effect 20 the operation of the electrodes and thus accomplish the passing of an electric spark at the proper instant in the cycle of engine operation.

The object of my present invention is to 25 provide an ignition mechanism of this class that is capable of being economically manufactured, one wherein the operation of the make and break devices, as well as the magneto rotor, are positively and properly 30 effected. Simplicity of construction is an essential feature of my present invention.

My invention will be more fully understood by referring to the following detailed 35 description wherein reference is made to the accompanying drawings in which,

Figure 1 is a vertical sectional view of 40 the ignition mechanism of my invention, this view being taken on a plane passing through the axis of the magneto rotor;

Fig. 2 is a view of the mechanism in end elevation; and

Fig. 3 is an isolated elevational view of 45 the electrodes which are disposed within the combustion chamber of the internal combustion engine with which the mechanism of my invention is associated.

Similar characters of reference refer to 50 similar parts throughout the several views.

Referring first to Fig. 1, I have illustrated at 4 a bracket arranged to be secured to the wall of an associated internal combustion engine by bolts, or other instrumentalities, passing through the apertures 5—5. The 55 wall of the combustion chamber of the en-

gine has been diagrammatically illustrated in dotted lines, as shown at 6. The bracket 4 comprises a substantially vertical wall 7 which, in the present embodiment of my invention, constitutes one of the side walls for the magneto generator, the other wall of 60 the magneto generator being formed by a somewhat similar wall 8 formed integral with the bracket 4 and having an aperture therethrough arranged to be closed by a plate 9 secured in position by suitable instrumentalities 10—10.

The magneto is conveniently of the unwound rotor type wherein an inductor is mounted for oscillation with respect to stationary generating windings to vary the 70 magnetic flux through said windings and thereby induce an electric current in the windings. The construction and operation of a magneto of this type are clearly shown and described in Patent No. 1180489 dated 75 April 25, 1916, and, therefore, for the purpose of the present invention it will suffice to say that the magneto field magnets 11—11 are mounted upon the shelf forming a part of the bracket 4 and that the magnets 80 11—11 have associated therewith pole pieces upon which are mounted suitable generating windings. The rotor, which in the present disclosure is an unwound metal inductor, is illustrated at 12, the aforesaid rotor being keyed upon a hollow shaft, or sleeve, 13 which is journaled in the bracket 4 and the closure plate 9, as clearly illustrated in Fig. 1, the left hand end of the said hollow shaft or sleeve 13 passing through a suitable aperture in the wall of the combustion chamber of the engine (Fig. 1) and being there provided with an arm 14 upon which is mounted one of the electrodes indicated at 14^a. The hollow shaft or sleeve 13 is 90 formed of conducting material and is connected in circuit with the magneto generating windings either directly or through the magneto frame work, the electrode 14^a constituting what is generally known as a 95 grounded electrode.

Keyed upon the right hand end of the hollow sleeve, or shaft 13, is a collar 15 which has formed integral therewith a pair of diametrically opposite arms 16 connected 105 by springs 17—17 with brackets 18—18 fixed with respect to the magneto frame work. It will thus be seen that the springs

17—17 normally serve to retain the magneto rotor 12 and electrode 142 in the positions illustrated in Fig. 1. Also formed integral with the collar 15 is a push finger 19 arranged to be engaged by an engine driven actuator, as for instance, a reciprocating rod, to move the shaft 13 and parts carried thereby against the tension of the springs 17—17 and then release the shaft whereupon the latter is returned to normal position by the springs 17—17. The general construction and mode of operation of the engine driven actuator of the type referred to are now commonly wellknown and are illustrated 15 in the patent previously referred to and I, therefore, have thought it unnecessary to illustrate such a device in the present disclosure.

Disposed within the hollow shaft, or sleeve, 13 is a unit comprising a sleeve 20 of metal having the cross section thereof reduced intermediate its ends, as clearly illustrated in Fig. 1, a sleeve of insulating material 21, and a metal conducting shaft 22. 25 Mounted upon the left hand end of the stem, or shaft, 22 (Fig. 1) is an arm 23 which carries an electrode 23^a coöperating with the electrode 14^a and normally held in the position shown in Fig. 3 by mechanism to be 30 presently described. The right hand end of the shaft, or stem, 22 is connected in circuit with the magneto generating windings by means of a conductor 24, it being understood that the electrode 23^a constitutes what 35 is commonly known as an insulated electrode. The sleeve 20, and parts disposed therewithin, extend beyond the hollow shaft, or sleeve, 13 at the right hand end of the latter (Fig. 1) and keyed upon the right 40 hand end of the sleeve 20 is a collar 25 having formed integral therewith an arm 26 the free end of which carries an adjustable screw 27. The screw 27 is normally held in engagement with a lug 28 formed upon the 45 shelf constituting a part of the bracket 4, the screw being thus held in engagement with the lug 28 by means of a spring 29 acting between the arm 26 and the lug 28.

It will thus be seen that the electrodes 14^a 50 and 23^a are normally held in the positions illustrated in Fig. 3 by the springs 17 and 29 respectively.

In the operation of the mechanism just described the engine driven actuating device operates to move the trip finger 19 in a 55 clockwise direction (Fig. 2) against the tension of the springs 17—17. When the trip finger 19 is thus moved against the tension of the springs 17—17 the rotor 12 and the 60 electrode 14^a are also operated. The electrode 14^a, after moving through a very small part of its arc of oscillation, engages the electrode 23^a and closes the circuit including the magneto generating windings. As the 65 several parts connected with the trip finger

19 continue to move against the tension of the springs 17—17 the electrode 23^a and parts connected therewith are carried with the electrode 14^a, this movement being opposed by the spring 29. When the trip finger 19 is released the springs 17—17 serve to quickly move the arms 16—16 and parts connected therewith back toward normal position. The spring 29, however, maintains the electrode 23^a in engagement with the electrode 14^a until the screw 27 abuts against the lug 28 at which time the electrodes are separated. I wish to have it understood that the adjustment of the several parts is such that the separation of the electrodes 14^a and 23^a is accomplished at the instant that the peak of the current wave induced in the magneto generating windings is attained.

From the foregoing description it will be seen that I accomplish proper operation of the current generating and electrode operating mechanism by a simple combination comprising very few parts. The mechanism may readily be adjusted to effect the passing of a spark at the exact instant necessary to most efficient engine operation and the operating parts of the magneto are accessible should it at any time be necessary to remove and repair or replace the same. It will, moreover, be understood that all of the operating parts in the magneto may be removed and the igniter operated with battery current if desired since the magneto rotor is merely keyed upon the shaft 13 and since all of the mechanism for controlling the igniter is mounted upon the bracket.

Having thus described my invention what I claim as new and desire to secure by Letters Patent of the United States is:

1. In combination with an internal combustion engine, a framework secured to the engine cylinder, a shaft supported by the framework, a pair of electrodes within the cylinder, one of which is mounted on said shaft, a magneto having the stator thereof mounted on said framework, the magneto rotor being fixed on said shaft, means on the shaft arranged to be engaged by an engine driven device to oscillate the shaft and rotor, together with springs positively connected with said shaft arranged to effect the operation of the electrodes and generate a current in the magneto windings when said shaft is oscillated by the engine driven device and released.

2. In combination with an internal combustion engine, a bracket secured to the engine cylinder, a shaft supported by the bracket, an electrode within the cylinder secured to the shaft, a magneto having the stator thereof on said bracket, the rotor attached to the shaft, means on the shaft arranged to be engaged by an engine driven member to oscillate the shaft and parts carried thereby, a second electrode disposed in

- proximity to the first and in the path thereof, together with spring means tending to move the second electrode toward the first, and relatively strong springs connected with the shaft arranged to quickly return the first electrode to normal and generate a current in the magneto when the shaft is oscillated by the engine driven device and released.
10. 3. In combination with an internal combustion engine, a pair of electrodes disposed within the combustion chamber of the engine, a shaft upon which one of said electrodes is mounted extending through the wall of the combustion chamber, a magneto having the rotor thereof rigidly fixed to said shaft, means whereby the shaft may be oscillated by an engine driven actuator and released, together with springs connected to said shaft arranged to effect the operation of the electrodes and move the rotor to generate a current in the magneto winding when the shaft is oscillated by the engine driven actuator and released.
15. 4. In combination with an internal combustion engine, a pair of electrodes disposed within the combustion chamber of the engine, a shaft upon which one of said electrodes is mounted extending through the wall of the combustion chamber, a magneto having the rotor thereof connected to and movable with said shaft, means whereby the shaft may be oscillated by an engine driven actuator and released, together with springs connected with said shaft arranged to effect the operation of the electrodes and actuate the rotor to induce a current in the magneto winding when the shaft is oscillated by the engine driven actuator and released.
20. 5. In combination with an internal combustion engine, a pair of electrodes disposed within the combustion chamber of the engine, a shaft upon which one of said electrodes is mounted extending through the wall of the combustion chamber, a magneto having the rotor thereof connected to and movable with said shaft, means whereby the shaft may be oscillated by an engine driven actuator and released, together with springs disposed outside of the combustion chamber and connected with said shaft arranged to effect the operation of the electrodes and move the rotor to generate a current in the magneto winding when the shaft is oscillated by the engine driven actuator and released.
25. 6. In combination with an internal combustion engine, a pair of electrodes disposed within the combustion chamber of the engine and located in proximity to each other, spring means normally holding one of said electrodes in a certain position, a shaft connected with the other electrode extending through the wall of the combustion chamber, a magneto having the rotor thereof connected to and movable with said shaft, means on said shaft whereby the latter may be oscillated and released by an engine driven actuator, together with spring means connected with said shaft arranged to operate the electrodes and generate a current in the magneto winding when the shaft is oscillated by the engine driven actuator and released.
30. 7. A mechanism of the class described comprising in combination, an electrode disposed within the combustion chamber of an engine and mounted upon an oscillatory shaft extending through the wall of the combustion chamber, a magneto having the rotor thereof connected to and movable with said shaft, means on said shaft whereby the latter may be oscillated by an engine driven actuator and released, spring means connected with said shaft arranged to return the aforesaid electrode to normal position and move the rotor to generate a current in the magneto winding when the shaft is oscillated by the engine driven actuator and released, a second electrode in the combustion chamber disposed in the path of the first, and means connected with said second electrode arranged to yield to permit said second electrode to move with the first when the shaft is operated by the engine driven actuator and arranged to return said second electrode to normal position when the shaft is released from the actuator.
35. 8. A mechanism of the class described, comprising in combination an electrode disposed within the combustion chamber of an internal combustion engine, a shaft connected with said electrode extending through the wall of the combustion engine, a magneto having the rotor thereof connected to and movable with said shaft, means whereby said shaft may be oscillated by an engine driven actuator and released, spring means connected with said shaft arranged to return the aforesaid electrode and rotor to normal positions when the shaft is released from the actuator, a second electrode located within the combustion chamber in the path of the first electrode but normally out of engagement therewith, together with resilient means connected with said second electrode arranged to yield when said shaft is operated by the actuator and thus brings the first electrode into engagement with the second, said resilient means serving, however, to return the second electrode to normal position when the shaft is released from the actuator.
40. 9. A mechanism of the class described comprising in combination with an internal combustion engine, a movable electrode disposed within the combustion chamber of the engine, a shaft connected with said electrode extending through the wall of the

- 4
- combustion chamber, an arm connected with said shaft at its outer end, a stationary abutment, spring means normally holding the arm in engagement with said abutment, 5 a second electrode disposed in proximity to the first but normally out of engagement therewith, a sleeve disposed around said first shaft carrying said second electrode, a magneto having the rotor thereof connected 10 to and movable with said sleeve, means whereby the sleeve may be oscillated by an engine driven actuator and released to effect the engagement of the electrodes and move the first electrode against the tension of its 15 associated spring; and relatively strong springs connected with said sleeve arranged to return the second electrode and the magneto rotor to normal position when the sleeve has been oscillated by the engine driven actuator and released.
10. An apparatus of the class described comprising in combination with a pair of electrodes disposed within the combustion chamber of an internal combustion engine, 25 a bracket arranged to be secured to the outside of the combustion chamber, a shaft on which one of said electrodes is mounted extending through the wall of the combustion chamber, said bracket having formed thereon a pair of parallel walls between which is carried the field magnet of a magneto, 30 said shaft extending through said parallel walls, and a rotor mounted on said shaft and movable in proximity to said field magnet, together with means for cyclically operating the rotor and electrodes in timed relation to each other.
11. Apparatus of the class described comprising a pair of movable electrodes disposed within the combustion chamber of an 40 internal combustion engine, a shaft on which one of said electrodes is mounted, spring means normally retaining said shaft in a certain position and adapted to quickly 45 turn the same toward normal when it is operated and released, a second shaft supporting the other electrode in the path of the first, together with spring means and an abutment coöperating with the second 50 shaft.
12. Apparatus of the class described comprising an electrode disposed in the combustion chamber of an internal combustion engine, a shaft on which said electrode is 55 mounted, spring means normally retaining the shaft in a certain position, means whereby the shaft may be oscillated against the action of said spring means and released, a second electrode disposed in the path of the 60 first, a shaft on which said second electrode is mounted, a stationary abutment, and spring means coöperating with said abutment to normally retain the second electrode in a certain position out of engagement with the first.
13. Apparatus of the class described comprising an electrode disposed in the combustion chamber of an internal combustion engine, a shaft on which said electrode is mounted, spring means normally retaining the 70 shaft in a certain position, means whereby the shaft may be oscillated against the action of said spring means and released, a second electrode disposed in the path of the first, a shaft on which said second electrode is 75 mounted, a stationary abutment, and spring means coöperating with said abutment to normally retain the second electrode in a certain position in the path of the first.
14. An apparatus of the class described 80 comprising in combination an electrode disposed within the combustion chamber of an internal combustion engine, an oscillatory shaft on which said electrode is mounted, a stationary abutment, a spring coöperating 85 with the abutment to normally retain the shaft and electrode in a certain position, a sleeve disposed around said shaft, a second electrode mounted on said sleeve and movable in the same plane with the first electrode, 90 spring means coöperating with said sleeve to normally retain the same in a certain position, and means whereby said sleeve may be oscillated against the action of its associated spring means and released, said first 95 electrode being engaged and moved by the second when the sleeve is oscillated against the action of its associated spring means.
15. The combination with a pair of electrodes disposed within the combustion chamber of an internal combustion engine, spring means normally holding a first one of said electrodes in a certain position, spring means and an abutment coöperating to normally retain the other electrode out of engagement with the first, together with means for moving the first electrode into engagement with the second, moving both electrodes against the action of their associated 105 spring means and releasing the electrodes 110 *seriatim*.
16. The combination with a pair of normally disengaged electrodes mounted for movement in the same plane around a common axis, spring means associated with each 115 electrode and mechanism for moving one of the electrodes into engagement with the other, then moving both electrodes against the action of their associated spring means and releasing the electrodes *seriatim*. 120
17. The combination with an internal combustion engine of a pair of normally disengaged electrodes mounted for movement in the same plane and around the same axis, spring means associated with each electrode, 125 a magneto comprising a rotor connected with one of said electrodes, and devices for moving the last mentioned electrode and rotor to effect the engagement of the electrodes, move both electrodes against the ac- 130

tion of their associated spring means, and release the electrodes *seriatim*.

18. The combination with an internal combustion engine of a pair of normally disengaged spark electrodes mounted for movement in the same plane around the same axis, a magneto comprising a rotor connected to and movable with one of said electrodes, relatively strong spring means 5 associated with the last mentioned electrode normally holding it and the rotor in a certain position, an abutment, a spring associated with the other electrode tending to move it past the abutment into engagement 10 with its coöperating electrode, together with means for moving the rotor and its associated electrode against the action of their common spring means and then release them whereby the electrodes are engaged, moved 15 against the action of their associated spring means while in engagement, and then moved together toward normal until the abutment 20

prevents further movement of one of the electrodes.

19. In combination with a pair of electrode carrying elements extending through the wall of the combustion chamber of an internal combustion engine, an electrode carried by each element, a stop for one of said elements, spring means normally retaining 25 said element in engagement with the stop, separate spring means normally retaining the other element in such position that the electrodes are separated, and means for moving the last mentioned element toward the 30 first so that the aforesaid elements are moved together and then to release it.

In witness whereof, I hereunto subscribe my name this 18th day of September, A. D. 1915

HARRY F. GEIST.
